(57) **CLAIM**

The ornamental design for a cigar cutter key chain, as shown and described.

DESCRIPTION

FIG. 1 is a perspective view of the cigar cutter key chain in accordance with the present invention;

FIG. 2 is a top plan view of the cigar cutter key chain shown in FIG. 1;

FIG. 3 is a front elevation view of the cigar cutter key chain shown in FIG. 1;

FIG. 4 is a rear elevation view of the cigar cutter key chain shown in FIG. 1;

FIG. 5 is an elevation view of one side of the cigar cutter key chain shown in FIG. 1, the other side being a mirror image thereof; and,

FIG. 6 is a bottom plan view of the cigar cutter key chain shown in FIG. 1.

The broken lines shown in the drawings are included for the purpose of illustrating environmental structure and form no part of the claimed design.
